UNITED STATES PATENT OFFICE.

FRANK GUENTHER, OF SAN MATEO, CALIFORNIA, ASSIGNOR OF ONE-HALF TO
WILLIAM MEINERSMANN, OF ELIZABETH, NEW JERSEY.

SIGNAL.

Application filed January 18, 1921. Serial No. 438,162.

To all whom it may concern:

Be it known that I, FRANK GUENTHER, a citizen of Germany, and resident of San Mateo, in the county of San Mateo and 5 State of California, have invented a new and Improved Signal, of which the following is a full, clear, and exact description.

In connection with automotive vehicles, accidents have often occurred due to the fact 10 that the doors were not properly fastened upon the driver starting, subsequent to which they opened, which frequently results in the damage of property due to the fact that the doors extend beyond the plane 15 of the running board.

With this in view, I have devised a signal, which will be inoperative upon the doors of the vehicle being opened, while the same is not in motion, but which will instantly 20 give the operator warning upon any of the doors opening while the vehicle is running.

A further object of my invention is the provision of a signal which will not alone indicate that a door is open, but which will 25 also show upon which side of the vehicle the open door is located.

Reference is had to the attached sheet 30 of drawings, as illustrating one practical embodiment of my invention, and in which drawings,

Figure 1 is a plan view of certain parts of an automotive vehicle, showing my improved signal system applied thereto when the same is in operation.

35 Figure 2 is a similar view showing the position of the parts with the doors open, but the vehicle not in motion, and

Figure 3 illustrates a detail of construction employed in connection with the operation of my signal.

In these views the reference numeral 5 indicates the dashboard or other convenient part of the vehicle, to which is applied visible and acoustical signaling means 6 45 and 7 respectively, which former may take the form of a light, the latter including a buzzer or other suitable annunciator.

A contact collar 8 suitably encircles the gear shift lever 9 at a point above the floor 50 board 10, from which it is spaced by any suitable means, such as supporting legs 11, insulation 12 being interposed between the legs 11 and ring 8 to prevent any grounding of the circuit.

55 Any suitable form of switch conven-

iently including a resilient bowed piece of material 13 mounting contact points 14 and normally holding the same in engagement with one another, is associated with each of the door jambs the strip 13 being capable 60 of being moved to hold the contacts 14 spaced, by means of the latch 15 when the door 16 is in closed position. One of the contact points 14 of the switch is grounded, as has been shown, the second contact point 65 being connected in series with one of the lamps 6 and the annunciator 7, the lead thence extending to the contact collar 8, at which point it terminates.

The door arranged upon the opposite side 70 of the vehicle is similarly equipped, and is in series with the opposite lamp 6, the common annunciator 7 and the common lead extending thence to the contact collar 8.

Encircling the gear shift lever 9 and insulated therefrom, as has been indicated by the reference numeral 17 is a contact ring 18, provided with resilient contacting fingers 19 adapted, when the lever has been actuated, to place the transmission "in 80 gear," i. e., when the collar 8 occupies a position other than concentric with respect to the ring 18.

A suitable source of energy, such as the ordinary, "starting, lighting and ignition 85 battery" 20 has one of its leads grounded in the usual manner, its opposite lead 21 extending to and being in contact with the ring 18.

It will now be appreciated, assuming that 90 the vehicle is not running, in other words, that the gear shift lever is in its neutral position as has been indicated in Figure 2, that the circuit is drawn between the contact fingers 19 and the ring 8, so that the 95 switches associated with each of the doors may be opened or closed without in the slightest effecting the circuit. This construction will permit a free opening and closing of the doors for the alighting and 100 entering of passengers within the vehicle without operating the audible and visible signals.

Further, upon the lever 9 being moved to a position in which the gears are in mesh, 105 in other words, when the car is running, upon any of the doors 16 being opened, as has been indicated in Figure 1, the circuit will be completed through the annunciator and through that light in circuit with the 110

switch associated with the open door. Thus the annunciator will serve to attract the operator's attention, and the light will instantly give him warning as to which door is open, which is a quality much to be desired, in that the operator must give almost his entire attention to the road to be traversed, and it will only be necessary for him to move his arm backward and swing that door shut, which is indicated as being open.

Obviously any suitable number of circuits might be employed in conjunction with a corresponding number of signals to indicate the position of any movable part of the car, also numerous modifications of structure might be resorted to without departing from the scope of my claim, which reads as follows:

I claim:

A signal, including in combination with the doors and gear shift lever of an automotive vehicle, switches associated with said doors, means cooperating with said doors and switches to hold the latter in open position when said doors are closed, a ring arranged around said gear shift lever and concentric with respect thereto when the same is in neutral position, contact fingers secured to said gear shift, levers, signals, a source of energy connected to said contact fingers, said switches, signals and ring co-operating to provide a closed circuit when one of said doors is opened, and the gear shift lever moved to a position other than its neutral point.
